Without further analysis, the foregoing will so fully reveal the gist of the present invention that others can, by applying current knowledge, readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. Method of treating the sufferings of vascular headache, which comprises administering to a patient suffering from the same an effective amount of at least one compound selected from the group consisting of alpha-picolinic acid diloweralkyl-amide and non-toxic acid addition salts thereof.

2. Method of treating the sufferings of vascular headache, which comprises administering to a patient suffering from the same an effective dose of alpha-picolinic acid diethylamide.

3. Method of treating the sufferings of vascular headache, which comprises administering to a patient suffering from the same an effective dose of a non-toxic acid addition salt of alpha-picolinic acid diethylamide.

4. Method of treating the sufferings of vascular headache, which comprises orally administering to a patient suffering from the same an effective amount of at least one compound selected from the group consisting of alpha-picolinic acid diloweralkyl-amide and non-toxic acid addition salts thereof.

5. Method of treating the sufferings of vascular headache, which comprises orally administering to a patient suffering from the same a unit dose of about 0.1-1 mg. of at least one compound selected from the group consisting of alpha-picolinic acid diloweralkylamide and non-toxic acid addition salts thereof.
